S. S. JACKSON,
WEFT REPLENISHING MECHANISM FOR LOOMS,
APPLICATION FILED OCT. 22, 1919.

1,407,423.

Patented Feb. 21, 1922.

UNITED STATES PATENT OFFICE.

SIMEON S. JACKSON, OF BOSTON, MASSACHUSETTS, ASSIGNOR, BY MESNE ASSIGNMENTS, TO THE STAFFORD COMPANY, OF READVILLE, BOSTON, MASSACHUSETTS, A CORPORATION OF MASSACHUSETTS.

WEFT-REPLENISHING MECHANISM FOR LOOMS.

1,407,423.

Specification of Letters Patent. Patented Feb. 21, 1922.

Application filed October 22, 1919. Serial No. 332,431.

To all whom it may concern:

Be it known that I, SIMEON S. JACKSON, a subject of Great Britain, residing at Boston, in the county of Suffolk, State of Massachusetts, have invented a certain new and useful Improvement in Weft-Replenishing Mechanism for Looms, of which the following is a specification, reference being had therein to the accompanying drawings.

10 The invention is an improvement in loom weft-replenishing mechanism of the class effecting replenishment by change of bobbins or cop-spindles. It has relation to the feeders or magazines of the said mechanisms, 15 and more particularly to the springs with which the filling-carrier supports of the said feeders or magazines are provided for engagement with the filling-carriers (bobbins, cop-spindles, or the like) placed in the feeders or magazines; and also has relation to the features of construction of the said supports providing for mounting the said springs in connection with such supports.

The invention provides a filling-carrier 25 engaging and retaining spring having an improved action and also less liability to breakage than springs which have been employed heretofore in certain instances; and also provides a filling-carrier support of a 30 novel construction especially adapted for the employment of springs of the said form, and for the ready and convenient application and removal of such springs.

The features of the invention may be employed at either or both ends of the filling-carrier. They are illustrated in the drawings as embodied in the tip-supporting means of a rotary feeder or magazine.

In the drawings,—

40 Fig. 1 shows, partly in vertical section, with the projecting flange of the frame-plate adjacent the butt-support partly broken away, a rotary feeder or magazine embodying the said features.

45 Fig. 2 is a back view of the tip-support of the feeder or magazine of Fig. 1, shown separately; and Fig. 3 is a view thereof in vertical section in the plane of line 3, 3, of Fig. 2.

50 Fig. 4 is a face view of the spring-engaging ring which is a portion of the said tip-support, showing the recurved tails of the tip-springs, with the springs in vertical section in the plane of line 4, 4; Fig. 3.

Fig. 5 is a face view on an enlarged scale 55 of the tip-engaging portion of a spring; Fig. 6 is an edge view thereof; and Fig. 7 is a view in longitudinal section on line 7, 7, of Fig. 5.

Fig. 1 shows the main portion of the stand 60 1 of a rotary feeder or magazine of ordinary type, and shows also the spindle 2 projecting horizontally from the upright portion of the said stand and serving for the support of the rotary portion of the feeder or magazine. 3 is the wheel or plate forming the support for the butts of the reserve filling-carriers 4 which are placed in the feeder or magazine. Fig. 1 shows only a portion of the width of the flange, of the said upright 70 portion of the stand, which projects over the periphery of wheel 3 and keeps the filling-carrier butts within the butt-pockets 3^a, 3^a, that are formed in the said periphery. 5 is the elongated hub or sleeve of the butt-support, said hub or sleeve fitting upon the said spindle 2. 6 is the ratchet-wheel upon the inner face of the butt-support, the teeth of which in practice are engaged by the devices (not shown) for rotating the feeder 80 or magazine forwardly and locking it from backward rotation. 7 is the wheel or plate of the tip-support, mounted by means of its hub 8 upon a reduced prolongation of the hub or sleeve 5 of the butt-support, and 85 secured thereon by means of clamping screws 9 at the proper distance from the wheel or plate of the butt-support. At 10 is the filling-end support, also mounted upon the prolongation of hub or sleeve 5, and fastened thereon by clamping screw 11. 12 is the filling-end holder projecting from the filling-end support 10, and upon which are wrapped the free extremities of the filling-ends that are extended from the filling-carries outward around the edge of the filling-end support.

With the exception of the tip-support, the parts thus far mentioned are not involved directly in the invention, and may 100 be of any approved character and construction.

As heretofore in some instances, the wheel or plate 7 of the tip-support preferably is made with a continuous rim or periphery. 105 As usual, the said wheel or plate is formed with a circular series of holes 7^a, 7^a, through its marginal portion, but inside the said

continuous rim or periphery, such holes constituting pockets for the accommodation of the tips of the filling-carriers 4 that are applied to the feeder or magazine as in Fig. 1. The carrier-engaging ends a' , a' , of the tip-springs enter into the empty pockets as in Fig. 3. As heretofore, the said ends a' are inclined backwardly as in Figs. 1, 3, 6 and 7, so that when the attendant upon the loom with which the feeder or magazine is connected pushes the tip of a filling-carrier inward radially into a pocket the pressure of said tip against the inclined surface of the corresponding spring-end a' will deflect such spring-end backward, permitting the carrier-tip to pass inward by the projecting bend a^2 adjacent the recess a^3 that is formed in the spring. As the tip reaches the recess, the spring-end closes forward against the tip so as to latch the latter in the pocket. A like backward deflection of the spring-end, followed by a return of the same forward, will take place at the time of the automatic transfer of a filling-carrier from the feeder or magazine to the shuttle of the loom.

In practice, tip-springs break as a result of frequently being bent, or of being subjected to undue strains in the operation of placing filling-carriers in the feeder or magazine, or because of the sudden and severe action when a filling-carrier is transferred to the shuttle, or as a result of various accidents. Thereupon, replacement is unnecessary.

The improved filling-carrier engaging and retaining spring which is one feature of the invention is substantially hair-pin shaped. It is made of a strip of flat spring-material of considerable length, doubled or recurved upon itself so as to form the two arms or branches a , a^2 of a U. The relative length of the two arms or branches with respect to each other may vary. Usually, the secondary arm, branch, or tail a^2 is shorter than the main arm or branch a , as in the case of the illustrated embodiment. The spring thus formed is applied to the back of the wheel or plate 7. An annular shoulder 7^b on the said wheel or plate, and with which the bend of the spring makes contact, serves as a stop to fix the distance of said bend from the axis of the feeder or magazine. The spring is intended to react, when the carrier-engaging arm is pressed backward, in virtue of engagement of the recurved arm or tail with a convenient abutment. Preferably, the bend of the spring is wide and rounded, as in the drawing, to lessen the liability to cracking and breakage at the bend as a result of the flexing of the spring in use. In practice, the proportions and precise form of the spring may vary, as well as the location of the abutment and the manner in which the spring engages with and reacts from the latter. In the illustrated embodiment the secondary arm,

branch, or tail a^2 , is turned backward and outward away from the main or engaging arm or branch a , and bears by its outturned face against an abutment constituted by the inner surface of a ring, b , at the back of the wheel or plate 7. Consequently, the spring reacts from the said surface of the said ring in a manner which causes its arm or branch a to press against the back or outer surface of the wheel or plate 7, and tends to hold the engaging end of said arm or branch in the corresponding pocket 7^a and in engagement with the filling-carrier tip as in Fig. 1 when the filling-carrier is in place. It will be obvious that when the arm a is bent backward by the action of the filling-carrier tip against the engaging end of such arm, as the filling-carrier is inserted into or driven from the pocket 7^a , the bending of the spring is distributed over a total length very much greater than that of the shorter straight springs, rigidly clipped and held at their inner ends, heretofore in use.

For convenience in construction, ring b in the present instance is made as a separate piece and attached by fastenings b' to the outer face of wheel or plate 7.

The manner and means of holding the springs in working relations with the other parts will vary in practice, according to the specific character of the construction adopted. As one feature of the invention, the ring b is shown provided with an overhanging lip b^2 , projecting slightly toward wheel or plate 7. This lip, by engagement with the extremity of the tail of a spring prevents outward radial movement of the spring. The tendency of the tail to spread away from arm a keeps said extremity in position to engage with the lip. The springs are shown as spaced apart from one another, and prevented from displacement sidewise, substantially as heretofore, namely by reason of their engaging ends being entered into the pockets 7^a of wheel or plate 7, and by means of lugs or projections, 15, 15, intervening between their inner portions. In the present instance the said lugs or projections are formed upon ring b and enter between the tails of adjoining springs.

In order to facilitate the operation of removing a spring when necessary, holes b^3 , b^4 are made through ring b , one for every spring in this instance. By pushing a suitable implement through one of these holes, the corresponding spring-tail a^2 may be pressed away from under the lip b^2 , and if at the same time the end of the long arm or branch of the spring is pressed inward through the pocket 7^a which it occupies, so as thereby to be pushed inward clear of the overhanging portion of the rim of wheel or plate 7, the spring will be free to be drawn endwise outward far enough to clear its bent

or bowed portion from ring b . Then, after 5 tilting the spring so as to turn the said bent or bowed portion away from the ring the said long arm may be withdrawn from the pocket 7^a . A spring may be inserted into an empty space between the ring and wheel or plate either by a reverse operation, or else by directly pushing it bent end first into such space, until the spring-tail springs past 10 and under the lip b^2 , which will lock such spring in working position. Shoulder 7^b of wheel or plate 7 will prevent the spring from occupying a position too far inward toward the center of the feeder or magazine.

15 The manner and means of combining ring b with wheel or plate 7 may vary in practice. It is shown as permanently fastened to said wheel or plate by rivets, but it may be attached removably thereto through the 20 employment of other attaching means. Permanent types of fastening-means are satisfactory when the general construction provides what may be termed "free" springs; i. e., when the springs are capable of being 25 applied, held in position, and removed, without the use of bolts and the like.

What is claimed as the invention is:—

1. In combination a filling-carrier engaging spring of U shape, comprising a branch 30 or arm which serves as a reaction-member and a second branch or arm constructed to engage and retain a filling-carrier, and a filling-carrier supporting member having a shoulder with which the bend of the spring 35 contacts, a wall serving as a reaction-abutment, and means to prevent displacement of the spring radially outward.

2. In a feeder or magazine for filling-car-

riers, in combination, a filling-carrier supporting member having spaced-apart walls, 40 one of them provided with a shoulder and a U-shaped filling-carrier engaging spring having its bend confined between the said walls, with one of its arms or branches engaged with said shoulder so that thereby 45 the spring is held from radial displacement.

3. In a feeder or magazine for filling-carriers, in combination, a U shaped filling-carrier engaging spring, and a filling-carrier supporting member having spaced-apart 50 walls between which said spring is entered, one of the said walls provided with a shoulder with which one arm or branch of the spring engages to hold the spring in place, and also formed with an opening 55 through which such arm or branch may be reached to push it out of engagement with said shoulder, to free the spring for removal.

4. In a feeder or magazine for filling-carriers, in combination, a U shaped filling-carrier engaging spring, and a filling-carrier supporting member having spaced-apart 60 walls between which said spring is entered, a shoulder with which the bend of the spring 65 engages so as to limit movement of the spring endwise in one direction and a shoulder with which one arm or branch of the spring engages to hold the spring from movement endwise in the other direction. 70

In testimony whereof I affix my signature in presence of two witnesses.

SIMEON S. JACKSON.
